CARBONATING AND DISPENSING
RECEPTACLE FOR LIQUIDS

Carl F. Lozon, Massillon, Ohio

Application March 13, 1937, Serial No. 130,733

3 Claims. (CL 225—22)

This invention relates to a device for carbonating and dispensing liquids, particularly beverages and carbonated water.

Heretofore it has been customary to make devices of this kind from glass and to reduce the danger from explosion by making the glass very thick and heavy and enclosing it in a metal sheath, the primary purpose in using the glass being to avoid tainting the contents by reaction with a metal which might otherwise be used instead of the glass. I have found that the liquids that are carbonated and dispensed from a device of this kind are not affected by contact with stainless steel and it is, therefore, one of the objects of my invention to provide a device that is so constructed as to be capable of being manufactured from stainless steel and thus be comparatively light and convenient to handle and yet have the requisite strength to safely withstand any pressure to which it may be subjected in use.

A further object of the invention is to provide a device of the kind referred to with an improved form of dispensing valve that is mounted on the exterior of the cover and not only practically leak-proof, but adapted for convenient operation.

A further object of the invention is to provide a device of the kind referred to that will be simple in construction, efficient in operation, and adapted for economical manufacture on a mass-production basis.

Other objects of the invention and the features of novelty will be apparent from the following description, taken in connection with the accompanying drawing, of which

Fig. 1 is a composite view, partially in side elevation and partially in central longitudinal section, of a device embodying my invention;

Fig. 2 is a detail section on the line 2—2 of Fig. 1;

Fig. 3 is a detail section on the line 3—3 of Fig. 1; and

Fig. 4 is an enlarged detail section on the line 4—4 of Fig. 1.

Referring to the drawing, 10 indicates the body of the receptacle, which is substantially cylindrical in form and provided with a concave dome-shaped bottom 11 and a slightly inturned top flange 12. As will be noted from Fig. 1, the opening 13 into the body 10 is only slightly less than the diameter of the body so that the interior of the body is readily accessible for cleaning, when the cover 14 is removed. The large top opening also permits ordinary-size ice cubes to

be readily put into the body 10 when desired. Adjacent its upper end the body 10 is provided with a circumferential series of lugs 15 having a substantially straight lower edge 16, these lugs being formed by pressing the metal outwardly without rupturing it. Any desired number of the lugs 15 may be provided but, in practice, I prefer to employ seven of these lugs equally spaced circumferentially.

The cover 14 is a substantially dome-shaped structure with a flat top 17 and an enlarged lower part 18 which forms a skirt that is adapted to telescope over the exterior of the body 10. The enlargement of the skirt portion of the cover also provides an internal shoulder or seat 19 against which a rubber gasket 20 is adapted to be positioned. As will be seen from Fig. 1, the lower edge of the gasket 20 is thickened so as to fit between the flange 12 and the skirt 18 and thereby seal the joint at this point, the internal pressure forcing the gasket into tight engagement with all of the metal parts with which it contacts, and the gasket thus serves as a means for effectively locking the cover 14 to the body 10 so that the cover cannot be accidentally or otherwise rotated relative to the body so long as there is pressure within the device.

There is a central opening in the top 17 and a tubular bulb-receptacle 21 extends through this opening as shown. The bulb-receptacle 21 has a flange 22 at its upper end which rests upon the top 17 and is secured thereto by welding or in any other suitable manner. The upper end of the flange 22 is provided with a radially extending lip 23 and this lip is spaced a short distance above the top 17. The body of the receptacle 21 is provided with two oppositely arranged longitudinal grooves 24 on its exterior, these grooves forming ribs 25 on the interior of the receptacle 21.

A cap 26 is arranged over the receptacle 21 and has its lower end arranged to engage the surface 17. The lower edge portion of the cap 26 has a plurality of internally projecting lug-like parts 27 formed therein by making shear cuts, parallel with the lower edge, and then pressing the metal between these cuts and the lower edge inwardly as will be seen from Figs. 1 and 3. There are preferably four equally spaced lug-like parts 27 and the lip 23 is provided with a similar number of equally spaced notches 28 which permit the cap 26 to be telescoped over the flange 22 and then, by rotating the cap 26, the parts 27 are positioned under the lip 23, as shown in Fig. 3. A downward depression 29 in the lip 23 is adapted

to be engaged by one of the parts 27 and act as a stop to limit the rotation of the cap 26 so that when one of the parts 27 is in engagement with the depression 29 the cap will be locked in position under the lip 23.

An internally threaded sleeve 30 is arranged in a central opening in the top of the cap 26 and is provided with a flange 31 which engages the exterior of the cap. The sleeve 30 is secured in position, after it is inserted in the opening in the cap 26, by turning over a flange 32 on the interior of the cap, as will be seen from Fig. 1. This may be done by means of a shaving tool which is forced over the inner end of the sleeve 30 and shaves down the metal to form the flange 32.

At the bottom of the receptacle 21 there is a piercing device which consists of a tubular member 33 having a flange 34 that engages the bottom of the receptacle 21, and an externally threaded part 35 which receives the nut 36 whereby the bottom of the receptacle 21 is clamped between the nut and the flange 34. The upper end of the piercing device is beveled, as shown at 37, to provide an efficient cutting edge that is adapted to pierce the bottom wall 38 of a bulb 39, arranged in the receptacle 21. There is a rubber gasket 40 at the bottom of the receptacle 21 and surrounding the piercing device, this gasket engaging the exterior of the bottom 38 of the bulb and forming a seal which prevents the escape of the compressed gas, along the exterior of the bulb, when the latter is pierced, as will be hereinafter described.

A screw 41 is arranged in the sleeve 30 and provided with a suitable handle 42 at its upper end. The lower end of the screw 41 is adapted to engage the upper end of the bulb 39 so that, by turning the screw, the bulb will be forced downwardly against the piercing device and cause the latter to puncture the bottom wall of the bulb and thus allow the gas to escape from the bulb through the piercing device and into the interior of the carbonating receptacle.

When the screw 41 is out of engagement with the bulb 39, the cap 26 may be rotated and removed, thereby making the bulb accessible for removal, and permitting the insertion of another bulb. The cap 26 is then replaced and rotated to its locked position, and this permits the charging operation to be repeated.

The skirt portion 18, of the cover 14, is provided with a circumferential series of bayonet slots which cooperate with the lugs 15. These slots are formed by pressing the metal of the skirt outwardly as shown at 43, the metal being cut along a line 44 and thereby forming an edge which is adapted to engage with the lower edge 16 of the lug 15. These bayonet slots are substantially hook-shaped and are widened at the lower edge of the skirt 18 so as to facilitate registration of the slots with the lugs 15. The gasket 19 is carried by the cover 14 and, in placing the cover in position on the body 10 it is telescoped over the lugs 15 and then rotated to effect the engagement of the edges 44 with the lower edges 16 of the lugs. From Fig. 1 it will be noted that the edge 44 is slightly inclined downwardly away from the vertical portion of the slot 43 and this, with the locking effect of the gasket 20, insures against accidental rotation of the cover, relative to the body 10, when the receptacle has a substantial pressure therein.

There is a flattened area 45 on one side of the cover 14 and a central opening in this area. Ar-

ranged in this opening is a tubular member 46 which has an external flange 47 that engages the area 45, and an internal flange 48 that cooperates with the flange 47 to secure the member 46 in position, the flange 48 being preferably formed in the same manner as the flange 32 of the sleeve 30. A short piece of rubber tubing 49 is telescoped over the member 46 and carries a tube 50 which extends to a point adjacent the bottom of the body 10. The tube 50 is preferably made of stainless steel or a tough, substantially unbreakable material which is neutral to any liquid that the receptacle is intended to receive and, for this purpose, I prefer to use a tube made of a composition known as tenite. By having the tube 50 carried by the rubber tube 49 it is free to move and cannot be damaged by ice cubes when the device is used as a shaker.

The outer surface of the flange 47 serves as a seat for a valve 51 which is preferably made of rubber and mounted in a housing 52 having a stem 53 secured thereto. A valve body 54, preferably in the form of a cup-shaped cylindrical stamping, is secured on the flat area 45 by having its flange 55 welded thereto. The stem 53 projects through the end wall of the body 54 and a gasket 56 is arranged on the interior of this end wall so as to prevent leakage along the stem. There is a washer 57 on the gasket 56 and a spring 58 engages this washer and also the housing 52, normally exerting sufficient force on the latter to hold the valve 51 against its seat, in opposition to the pressure within the receptacle. A trigger 59, in the form of a channel-shaped stamping, is connected with the valve stem 53 by a pivot pin 60 and the portion 61 of this trigger is arranged to fulcrum on the end wall of the valve body 54 so that when the trigger is depressed the valve 51 will be lifted off its seat and permit the contents of the receptacle to be discharged through the tube 50 and into the interior of the valve body. There is an opening 62 in one side of the valve body, and a nozzle 63 is pressed over the valve body 54 and has a discharge opening 64 which registers with the opening 62 so that the contents of the receptacle may be discharged through this nozzle.

For the purpose of safety various parts of the apparatus are so relatively proportioned that it will be impossible to so charge the receptacle as to have an excessive or dangerous pressure therein. The body 10, in one commercial form of the apparatus, has a capacity of approximately sixty cubic inches of liquid when filled to the maximum. Under these conditions and with the cover 14 in position the free space within the cover is approximately eighteen and one-half cubic inches. The bulbs for which this apparatus is designed have a charge of from one hundred twenty-five to one hundred thirty grains under a pressure of about nine hundred pounds per square inch. Under these conditions, when the charge in the capsule is released into the receptacle the maximum pressure will not exceed one hundred fifty pounds per square inch and, when the receptacle is used for charging water with CO₂ gas, the absorption of the gas, by the water, will rapidly reduce the pressure to about fifty pounds per square inch, and this pressure will be sufficient to discharge all of the liquid through the nozzle 63.

The conditions just referred to are those in which the maximum pressure can be produced within the receptacle by the capsule charge and, of course, if the body 10 is only partially filled

with water the maximum pressure that would be attained within the receptacle would be lower because of the increased amount of free space, for the gas, above the water. Since the parts have been designed so as to permit the body 10 to be completely filled with water and, nevertheless, prevent a dangerous pressure within the receptacle, the construction and arrangement of the parts of the receptacle constitute an important safety feature.

All of the metal parts of the apparatus are preferably made of stainless steel and thus not only have the requisite strength but are non-corrosive and avoid tainting of the liquids but permit the apparatus to be maintained at all times in a thoroughly sanitary condition.

Having thus described my invention, I claim:

1. In a combined carbonating and dispensing device, a receptacle, a removable pressed metal cover secured thereon, said cover having a portion provided with an opening, a tubular member arranged in said opening and having integral external and internal flanges engaging the outer and inner surfaces, respectively, of said portion, a valve body secured on the exterior of said cover independently of said member, a valve within said valve body and adapted to close the opening through said tubular member, said valve body having a discharge opening in its side wall, a spout surrounding said valve body and having a discharge port which registers with said discharge opening, and means for actuating said valve.

2. In a combined carbonating and dispensing device, a receptacle, a removable pressed metal cover secured thereon, said cover having a flat portion provided with an opening, a tubular member arranged in said opening and having integral external and internal flanges engaging the outer and inner surfaces, respectively, of said flat portion, a valve body secured on the exterior of said cover independently of said member, a valve within said valve body and adapted to close the opening through said tubular member, said valve body having a discharge opening in its side wall, a spout surrounding said valve body and having a discharge port which registers with said discharge opening, a spring within said valve body for normally holding said valve in its closed position, and a lever for opening said valve.

3. In a combined carbonating and dispensing device, a receptacle, a removable pressed metal cover secured thereon, said cover having a flat portion provided with an opening, a tubular member arranged in said opening and having integral external and internal flanges engaging the outer and inner surfaces, respectively, of said flat portion with one of said flanges welded to the surface which it engages, a valve body welded to the exterior surface of said flat portion independently of said member, a valve within said valve body and seated on the outer end of said tubular member, said valve body having a discharge outlet, and means for opening and closing said valve.

CARL F. LOZON.
